United States Patent Office

Des. 186,298
Patented Oct. 6, 1959

186,298

SAFETY PIN

Kurt Gaupp, Maplewood, N.J., assignor to Forstner, Inc.,
Irvington, N.J., a corporation of New Jersey

Application March 16, 1959, Serial No. 55,000

Term of patent 7 years

(Cl. D86—10)

Fig. 1

Fig. 2

Fig. 3

Fig. 4

Fig. 5

Fig. 1 is a top plan view of a safety pin embodying my new design;

Fig. 2 is a side elevational view thereof;

Fig. 3 is a bottom plan view;

Fig. 4 is a left-hand end view of the safety pin as shown in Fig. 2; and

Fig. 5 is a right-hand end view thereof.

I claim:

The ornamental design for a safety pin, substantially as shown.
